UNITED STATES PATENT OFFICE.

THEODORE DOUGLAS, OF SCARBORO, NEW YORK.

RAILWAY-CAR VENTILATOR.

1,116,576.

Specification of Letters Patent. Patented Nov. 10, 1914.

Application filed August 13, 1912. Serial No. 714,851.

To all whom it may concern:

Be it known that I, THEODORE DOUGLAS, a citizen of the United States, and resident of Scarboro, county of Westchester, State 5 of New York, have made a new and useful Invention in Railway-Car Ventilators, of which the following is a specification.

My invention is directed primarily to appliances adapted for use on railway cars to 10 provide a uniform, and automatically controlled inflow of air into the car, and a corresponding flow of the used and vitiated air from the car through openings in its roof.

My invention will be fully understood by 15 referring to the accompanying drawings, in which,

Figure 1 is a cross section of a car showing the intake ventilators in the floor of the car, and the outlet ventilators in its roof, 20 and the vanes for their automatic regulation. Fig. 2 is a view, partly in section and partly in elevation, along the line X, X, looking toward the side of the car as indicated by the arrow N.

25 The ventilation ordinarily provided in a railway car consists of such change of air as may result from leakage into the car through its various openings, and of the exit of the vitiated and heated air through 30 bratticed, or window-like openings, in its monitor roof. This inclosed air is in some cases stirred up and circulated by means of fans which do not in any sense increase the quantity of air within the car, influence its 35 purity, nor do they tend to bring in a fresher air from its exterior.

In the present invention provision is made 40 for the impelled entrance of air into the car through openings in its floor, such openings being preferably located beneath the seats and below such heating devices as may be employed. This entrance is impelled by 45 means of swinging scoops located transversely below the car and under the floor openings. On the movement of the car, and as a result of that movement, the air is 50 picked up by the scoops and forced upward through the openings, through a cleansing chamber, through the heater, through the 55 body of the car, and through the outlet ventilators in its roof. This feature of the location of the intake openings is particularly advisable in subway service as the air in the tunnel lying immediately above the floor is not only the coolest air in the tunnel, but

presumably the best, assuming that it is freed from dust particles.

Referring now to the drawings in detail, and first to Fig. 1, where a complete application of the invention is shown, A represents the floor, B the roof, and C, C the sides of a car. 1, 1 are swinging scoops located below the openings 2, 2 in the floor of the car. 3, 3 are perforated housings covering the openings, and 4, 4 are roof ventilators. 60

A more detailed arrangement of the inlet parts is shown in Fig. 2, in which 1^a and 1^b are swinging scoops, 2 the opening in the floor, 3 the housing above the opening in the floor, 5, 5, 5 heating or cooling coils, 6 the coil support, 7 a screen immediately above the opening in the floor and constituting the bottom of the chamber 8, having as its walls and roof the coil-support 6. It is designed to have this chamber 8 loosely 70 packed with mineral wool, or other suitable screening or filtering substance, to remove the dust from the air before it enters the car. Provision is made for the removal of the dirty wool and the insertion of fresh 75 wool through openings provided in the ends of the housings 3, 3, see Fig. 1, as at 9, 9. 10, 10, 10 are springs working under such tension as to loosely hold the scoops 1^a and 1^b in their normal position relative to each 80 other and to prevent their undue swinging at times of quick starting and stopping of the car. 11, 11 are brackets supporting the scoops, there being one at each end, and from which they are suspended by means of 85 bolts or rods providing for their swinging motion.

The operation of the devices is as follows: Referring now to Fig. 2, the car is assumed 90 to be moving in the direction indicated by the arrow M. On the movement of the car, and as a result of that movement, the air is 95 picked up by the scoop 1^a and forced upward through the opening 2, through the screen 7, through the chamber 8 loosely filled with 100 mineral wool, around the heating or cooling coils 5, and out through the openings in the housing 3 as indicated by the small arrows. It circulates through the car, having a rising 105 tendency, see Fig. 1, and finds exit through the ventilators 4, 4. As the volume of air forced into the car by means of the scoop 1^a would be in proportion to the speed of the car, the inflowing volume is regulated by an 110 automatic movement of the scoop in gradu-

- ally increasing and decreasing the area of the opening at the top of the scoop, as the speed of the car increases and decreases. As the speed of the car increases the pressure of the air upon the scoop will be such as to deflect it into some position between the two extreme positions shown at H and I. The greater the speed of the car the greater will be the degree of deflection and the smaller will be the opening at the top of the scoop through which the air must pass. The volume of the air entering the car would be proportionate to the car-speed were it not for this automatic regulation, through which the volume of air entering the car is made nearly constant for all speeds, and undue drafts are avoided.
- To provide for a change of direction in the movement of the car, and in order that the device may operate in either direction, the scoops are placed in pairs, back to back, as shown in the drawing, and the scoops are held in their normal relation to each other and to the opening by means of springs of only sufficient strength as to prevent undue swinging and noise. When the direction of the car is reversed, the scoop ^{1b} becomes active and operates in the same manner as described for ^{1a}, which ceases to operate.
- Undue drafts are prevented by the housings 3, 3 and the screening devices within them, in which the air currents are broken up and the air cleansed. In the winter time the heating of the incoming air may be provided for by locating the heating devices of the car within the housings as above described, or the cooling of the air may be so provided for.
- The number of scoops provided for each car should be proportionate to its passenger capacity.
- I do not limit myself to the special application and the special details of construction shown as I believe it is broadly new with me to provide a combination of means designed to automatically compel an entrance into a railway car of air through openings in its floor, to maintain approximately constant the volume of inflowing air irrespective of the speed of the car, or its direction of mo-

tion, by means of scoops located below its floor and designed to swing upon supporting bearings; to provide a means of cleansing the air and through a cleansing agent which may be quickly renewed.

55

I do not limit myself to the use of my invention on railway cars as the same may be applied to other moving vehicles, and in other ways.

Having thus described my invention, what I claim and desire to secure by Letters Patent of the United States, is,

1. In combination with a moving vehicle, an intake ventilator consisting of a curved part, or scoop, supported therefrom and faced in the direction of the motion of the vehicle to pick up air and force it into the interior of the vehicle, means for holding the scoop in an open position, openings in the top of the scoop for the discharge of the entrained air into the interior of the vehicle and so supported as that when the vehicle is in motion, and as a result of the impact of the air upon the scoop, the scoop will be deflected, and approximately proportionately to its deflection will close the discharge openings from the scoop, for the regulation of the inflow of the air into the vehicle, substantially as described.

70

2. In combination with a moving vehicle, an intake ventilator consisting of curved parts, or scoops, placed back to back, and supported therefrom, stabilizing means between the scoops and their supports, openings in the upper sides of the scoops for the discharge of the air into the interior of the vehicle, and so supported as on the deflection of the scoops to approximately proportionately close these openings in proportion to the amount of the deflection of the scoops, for the regulation of the inflow of air, irrespective of the speed of the vehicle and of its direction of motion, substantially as described.

75

In testimony whereof I affix my signature in presence of two witnesses.

THEODORE DOUGLAS.
